UNITED STATES PATENT OFFICE.

JULIUS PATTEN, OF DUISBURG, GERMANY.

SHIN-BONE-PROTECTING SHIELD FOR SPORTS.

Application filed December 14, 1926, Serial No. 154,801, and in Germany October 31, 1925.

Protecting shields for parts of the human body have become known which consist of a curved plate which is fixed on the body by means of straps so that the shield is slightly spaced from the body. Protecting devices of this type are mainly used to protect the breast and to intercept feeble strokes, caused for instance by balls.

According to the invention an insertion of elastic material is substituted for the supporting straps, said insertion extending over the shin-bone under the protecting shield so that even the strongest shocks are intercepted.

An embodiment of the invention is shown, by way of example, in the accompanying drawing, in which

Fig. 1 shows the protecting shield in front elevation.

Fig. 2 is a section on line 2—2 Fig. 1.

Fig. 3 shows in side elevation the protecting shield for the shin-bone fixed on the leg.

The protecting shield consists of a plate *a* and shield of semi-circular cross section, which has outwardly flanged long edges *c* with which the side edges of an insertion *b* engage. The insertion *b* is of such width

that, when it is fixed on the inner surface of the shield *a*, a free space *f* is left between the shield and the insertion. The lower edge *d* of the shield *a* is cut out as shown so that the shin-bone protector fits better over the ankle-joint. The protecting shield is attached on the leg by means of elastic straps *e* which are passed through eyes *g* of the shield *a*. A stretching device of any convenient known type may be arranged in or on each strap *e*.

I claim:—

A shin-bone protecting shield for sports, comprising in combination, a shield of semi-circular cross section, outwardly flanged edges on the long sides of said shield, an insertion of elastic material fixed in the flanged edges of said shield and extending in space relation thereto across the inner side of said shield so that a free space is formed between said inner surface of said shield and said insertion, and straps of elastic material for attaching said shield on the leg.

In testimony whereof I affix my signature.

JULIUS PATTEN.
